UNITED STATES PATENT OFFICE.

WILLIAM J. KELLY, OF CLINTON, IOWA.

GEARING SYSTEM.

1,168,080.

Specification of Letters Patent.

Patented Jan. 11, 1916.

Original application filed January 21, 1914, Serial No. 813,552. Divided and this application filed May 15, 1914. Serial No. 838,823.

To all whom it may concern:

Be it known that I, WILLIAM J. KELLY, a citizen of the United States, residing at Clinton, in the county of Clinton and State 5 of Iowa, have invented new and useful Improvements in Gearing Systems, of which the following is a specification.

This application is filed as a division of my co-pending application Serial Number 10 813,552, filed January 21, 1914, for improvements in washing machines.

The present invention relates to improvements in gearing and proposes a system of gearing for transmitting power from an 15 electric or other motor to two structurally independent instrumentalities employed in combination with one another and designed to be independently regulated or controlled, notwithstanding their simultaneous operation 20 from the common source of power. While the invention is perhaps capable of limited general application, its greatest utility will doubtless be for the operation of washing machines and wringers and it is for 25 this useful application that the invention is especially designed.

It is customary in the construction of domestic washing machines to include a wringer in the equipment, to support the 30 wringer from the tub, and to employ gearing which drives the washing mechanism and the wringer from a common source of power.

The improved gearing of the present invention in its application to domestic washing 35 machines, embodies a common driving shaft for the washing mechanism and the wringer and gear connections between said shaft and the washing mechanism and the wringer of such nature that the operation of the wringer 40 may be interrupted without interference with the operation of the washing mechanism or by reversing the electric or other motor which drives the power shaft, the wringer may be reversed without entailing 45 any interruption of the operation of the washing mechanism. The invention avoids the cumbersome reversing gearing which is ordinarily employed and provides gearing which is of simple, compact, and readily 50 accessible structural nature.

An embodiment of the invention is illustrated in the accompanying drawings wherein:

Figure 1 is a side elevation of a machine 55 in which the features of the invention are

incorporated; Fig. 2 is an elevation in a plane at right angles to the plane of Fig. 1, certain parts being shown in section; Fig. 3 is a top plan view with the cover of the gear case removed to show the gearing; Fig. 4 is a detail sectional view on line 4 of Fig. 3.

Similar characters of reference designate corresponding parts throughout the several views.

The invention is illustrated in connection with a washing machine which includes a tub 1 having a cover 2 and a support 3 to which the cover is hinged. A wringer 4 is included in the equipment of the machine, 70 the wringer being mounted in upright relation upon a supporting base 5 which adjoins the cover 2 and extends at a right angle to the support 3.

The washing mechanism may be of any 75 approved construction comprising a suitable dolly head, (not shown), which, in the embodiment disclosed, is operated by an oscillatory lever 6 movable in a vertical plane and supported by a suitable bracket 7 set 80 into the cover 2.

The power for operating the washing mechanism and the wringer is supplied by a reversible electric motor 8 which is suitably supported below the tub and is connected by belt or equivalent gearing 9 to a power shaft 10.

The lever 6 is operated from a shaft 11 through the intermediary of a crank arm 12 on said shaft and a link 13 connected to 90 said crank arm. The lever 6 is to be disconnected from its operating means when the cover 2 is raised, and with this object in view, the link 13 includes a frame 14 having its side bars recessed in their under edges 95 as at 15 and the lever 6 is provided at its upper end with laterally-projecting lugs 16 which engage in the recesses 15. Beyond the frame 14, the link 13 is continued to provide a handle 17 by means of which said 100 link may be raised or lowered in effecting its engagement or disengagement relative to the lever 6.

The shaft 11 in the embodiment shown extends parallel to the power shaft 10 and is 105 driven from the latter by suitable gearing comprising a worm 18 on the shaft 10, a worm wheel 19 operated by said worm, a bevel pinion 20 fast with the worm wheel 19, and a bevel pinion 21 fast on the shaft 11 110

and in mesh with the pinion 20. The worm wheel 19 and pinion 20 are mounted upon a shaft 22 which operates the wringer 4, driving the lower roll of said wringer by means 5 of gears 23 and 24. The shaft 22 is rotated by the worm wheel 19 but is splined or otherwise slidably related to said worm wheel and has on its free end a knob 25 by means of which it may be moved in the direction of 10 its axis. This shaft 22 is slideable in order that its gear 23 may be, at will, engaged with or disengaged from the gear 24. In this way the operation of the wringer may be interrupted and resumed in accordance with circumstances and without in any way interrupting the operation of the dolly head.

The reversal of the rotation of the wringer rolls is effected by reversing the electric motor 8, the operation of which is controlled, 20 by a suitable reversing switch 26, conveniently secured at one side of the wringer stand.

The gears 18, 19, 20 and 21 are preferably arranged in a casing 27, which serves as a 25 container for lubricant and is constructed to provide bearings for the shafts 22 and 10. The gears 23 and 24 are preferably arranged within a casing 28 suitably secured to the wringer stand.

Having fully described my invention, I 30 claim:—

1. In a gearing system of the class described, in combination, a support, a transverse power shaft mounted on the support, 35 an upright mechanism operating element, a horizontal mechanism operating shaft, a transverse shaft extending at an angle to said horizontal shaft, connections between the last named transverse shaft and the upright element to oscillate the latter, a worm 40 on said power shaft, a worm wheel operated by said worm, bevel gearing between the worm wheel and said last named transverse shaft, a longitudinal shaft upon which said 45 worm wheel is mounted, the worm wheel being splined upon the longitudinal shaft and the latter being slidably mounted, a pinion mounted on said horizontal operating shaft

and a pinion fixed on said longitudinal shaft and engaging said first named pinion in one 50 position of said longitudinal shaft.

2. In a gearing system of the class described, in combination, a support, a transverse power shaft mounted on the support, 55 an upright mechanism operating element, a horizontal mechanism operating shaft, a transverse shaft extending at an angle to said horizontal shaft, connections between the last named transverse shaft and the upright element to oscillate the latter, a worm on said power shaft, a worm wheel operated by said worm, bevel gearing between the worm wheel and said last named transverse shaft, a longitudinal shaft upon which 60 said worm wheel is mounted, the worm wheel being splined upon the longitudinal shaft and the latter being slidably mounted, a pinion mounted on said horizontal operating shaft, a pinion fixed on said longitudinal shaft and engaging said first named pinion 65 in one position of said longitudinal shaft and a casing inclosing said worm wheel and providing bearings for the horizontal shaft.

3. In a gearing system of the class described, in combination, a support, a transverse power shaft mounted on the support, 75 an upright mechanism operating element, a horizontal mechanism operating shaft, a transverse shaft extending at an angle to said horizontal shaft, connections between the last named transverse shaft and the upright element to operate the latter, a worm on 80 said power shaft, a worm wheel operated by said worm, bevel gearing between the worm wheel and said last named shaft and a longitudinal shaft geared to said horizontal shaft to drive the latter and upon which 85 said worm wheel is mounted.

In testimony whereof I have hereunto set my hand in presence of two subscribing witnesses.

WILLIAM J. KELLY.
